UNITED STATES PATENT OFFICE.

JOHN B. BURDETT, OF CHICAGO, ILLINOIS, ASSIGNOR, BY MESNE ASSIGNMENTS, TO NATIONAL PNEUMATIC COMPANY, A CORPORATION OF WEST VIRGINIA.

DIVIDED DOOR FOR STREET-CARS OR OTHER PURPOSES.

1,134,668.

Specification of Letters Patent.

Patented Apr. 6, 1915.

Application filed July 25, 1908. Serial No. 445,393.

To all whom it may concern:

Be it known that I, JOHN B. BURDETT, a citizen of the United States, residing at Chicago, in the county of Cook, State of Illinois, have made a certain new and useful Invention in Divided Doors for Street-Cars or other Purposes, of which the following is a specification.

The invention relates to divided doors.

10 The object of the invention is to provide a door divided into two portions, and so arranged and connected that they move in different directions in opening and closing.

15 A further object of the invention is to provide a divided door and means whereby, in opening, the portions of the door move in directions at right angles to each other.

20 A further and more restricted statement of the object of the invention is the provision of means whereby, in a divided door for street cars or other purposes, one portion thereof is moved into position to form a step while another portion thereof is moved into open position.

25 Other objects of the invention will appear more fully hereinafter.

The invention consists substantially in the construction, combination, location and relative arrangement of parts, all as will be 30 more fully hereinafter set forth, as shown in the accompanying drawing, and finally pointed out in the appended claims.

Referring to the accompanying drawing, and to the various views and reference signs 35 appearing thereon, Figure 1 is a view in side elevation of the end of a car, parts broken out, parts broken off, and parts in section, showing application of a divided door construction and a form of interconnecting mechanism embodying the principles of my invention, and showing in full lines the position of the parts with the door closed, and in dotted lines the door open. Fig. 2 is a broken transverse section on the line 2, 2, Fig. 1, looking in the direction of the arrows, with the door closed. Fig. 3 is a diagrammatic plan of the same.

45 The same part is designated by the same reference sign wherever it occurs throughout the several views.

In the practical operation of street or other cars according to modern practices and methods, it is becoming more and more desirable to provide inclosed 55 platforms at the ends of the car, and

to provide the platforms with side doors, in place of or in addition to the ordinary doors between the platform and the car body. In constructing new cars embodying this method and practice, it is customary to extend the floor of the car body to the extreme ends of the car so that the floors of the platforms at the ends of the car are on a level with the floor of the car body and forms continuations thereof. In this case 60 the problem of providing the vestibules or platforms at the ends of the car with sliding doors so that such doors may slide into side pockets formed in the sides of the car, becomes an easy one. In converting the old 65 style of cars into the inclosed platform type, however, a more difficult problem has arisen since it is not only necessary to provide the sliding or other side doors, but it is also necessary to make proper provision for steps. Moreover, in most instances of old style cars 70 the platforms or vestibules, or the floors thereof, are on a lower level than the level 75 of the floor of the car body.

In accordance with the principles of my 80 invention I propose to employ a divided door in the side of the car platform or vestibule which, when closed, completely incloses the platform or vestibule, and one portion of which, the upper portion, may 85 slide into a pocket formed in the side of the car, while the other or lower portion thereof swings down at right angles to the direction 90 of movement of the upper portion, to form a step, the lower level of the platform floor, with reference to the floor of the car body, making it impractical for the entire side platform door to slide into a pocket in the side 95 of the car body. In the accomplishment of the objects and purposes of my invention, therefore, and as above indicated, I employ a divided door, the upper portion mounted to slide in a plane parallel with that of the side of the car, while the lower portion is 100 hinged so as to swing downwardly into position for use as a step when the upper portion is moved into its receiving pocket, and to swing upwardly into position to coöperate with the upper portion to close the platform or vestibule side doorway or opening, when such upper portion is moved into its 105 closed position. I also propose to so connect the two portions of the doors as to cause coincident and coöperative movements thereof, and I so arrange such connections 110

that the relative speeds of movement of the sections or portions of the door varies according to the relative positions thereof.

In the accompanying drawing I have indicated a construction exemplifying the principles of my invention as applied to street cars and wherein the floor of the platform at the end of the car is at a lower level than the floor of the car body. 5
 10 In the drawing reference sign 5, designates the floor of the car body, 6, the floor of the platform at the end of the car, 7, the upper portion of the divided door, and 8, the lower portion thereof. The lower portion 15 of the door is carried by castings or brackets 9, supported upon a rock shaft 10, carried by hangers 11, depending from the under side of the platform adjacent the doorway in the side thereof, whereby, when 20 said shaft is rocked the lower section 8, of the door is rocked or swung into position for use as a step, or into position to coöperate with the upper section of the door to close the doorway, according to the direction in 25 which said shaft is rocked. The upper section or portion 7, of the door may be supported in the ordinary manner of sliding doors, as for instance, by means of hangers 12, and is arranged to slide into a pocket 30 formed in the side of the car body, as indicated at 13. Any desired or well known form of door operating mechanism may be employed. As illustrative of an operative embodiment, I have shown a pivoted lever 35 14, having sliding connection with the door. By rocking said lever the door is moved into or out of closed position, according to the direction of operation of the lever, and when in open position is received in the 40 pocket 13. The lever 14, may be rocked in many different ways, and many different arrangements of connections between the sections 7, 8, of the door may be devised for securing coincident movement of said sections but in different directions. For instance, and by way of illustration, an operating handle or lever 16, is provided for 45 rocking a bell crank arm 17, which is connected by a link 18, with one arm of a bell crank lever 20, which is pivoted at 15, said operating handle or lever 16, being also connected to operate the door moving lever 14. To another arm 21, of the bell crank lever is 50 connected one end of a link 22, said link being connected at its other end to a crank arm 23, on the rock shaft 10, whereby, when the operating lever 16 is rocked the lever 14 is also rocked to shift or move the upper 55 section of the door while at the same time the section 8, of the door is coincidentally moved. By the relation and arrangement 60 of lever and link connections above described, it will be seen that the relative speeds of movement of the two sections of

the door vary according to the positions of said sections. The upper section of the door begins to move slowly toward its closed position, but rapidly accelerates its speed until it approaches its closed position when its 70 speed is again reduced. So, too, in opening, the lower section of the door begins its movement slowly and then accelerates, but slows down again as it approaches its lowered position. This result is due to the arrangement of crank arm connections through which the door sections are operated, and the shifting leverages exerted thereby by reason of the relation and arrangement and the arcs through which they 75 turn. It is obvious, however, that my invention, in its broadest scope as defined in the claims, is not to be limited or restricted with respect to the mechanism employed to 80 operate the door or the sections thereof. 85

In practice I prefer to so arrange the link 18, that when the upper portion 7 of the door is in its open position, that is, is in the pocket in the side of the car, the point of connection of said link with the crank arm 17, will pass closely adjacent a line joining the axis of said crank arm and the point of connection of said link 18, with the arm 19, as indicated in Fig. 1, thereby making the action a substantially dead center action, so that when the upper portion of the door begins to move toward its closed position a powerful action of the crank arm 17, is exerted to initiate the raising movement of the lower portion of the door, this action resulting from the crank arm moving off its dead center position, helps to overcome the weight of the section 8, of the door in moving from its lowered position. 90 If desired, and in order to assist in balancing the weight of the section 8 of the door when in its lowered position, I may attach a spring 25, to the crank arm through which the section 8, of the door is operated, in 95 such manner and relation as to be put in tension when said section of the door is moved into its lowered position. 100

As above noted my invention in its broadest scope and as defined in the claims is not to be limited in respect of the means employed to operate the sections of the doors, nor with respect to the point from which such operation is controlled, the arrangement shown being designed merely as 110 an illustrative form of mechanism for accomplishing the desired objects. 115

The platform or vestibule may be separated from the body of the car by the usual doors 26, 27, which move transversely of 120 the car when opening or closing. These doors 26, 27, are mounted and arranged in the ordinary manner to separate the vestibule or platform from the body of the car. 125

I do not claim herein the door construc- 130

tion, *per se* as the same forms the subject-matter of my application, Serial No. 584,393, filed Sept. 30, 1910, and divided out of this application.

5 Having now set forth the object and nature of my invention and a construction embodying the principles thereof, what I claim as new and useful, and of my own invention, and desire to secure by Letters

10 Patent is:

1. A car having a floor, a doorway, and a side pocket, in combination with a door section to close the upper portion of said doorway, and adapted to slide into said pocket

15 in opening, and a member hinged beneath the floor at the doorway and adapted to rock into position to close the lower portion of the doorway when closed and to form a step below the doorway and floor when

20 closed.

2. A car having a platform, a side doorway for the platform, a movable door section to open and close the upper portion of said doorway, a movable member hinged be-

25 low the floor of the platform to be rocked into and out of position to close the lower portion of the doorway, said member when in open position forming a step below the level of the platform floor, and connections 30 for coincidently moving said door section and member into and out of closed position.

3. A car having an end platform and a side door therefor, said door made in sections, one section being mounted to rock in

35 opening, into position below the level of the platform floor to form a step and the other section mounted to slide out of the entrance to and from the platform, said sections being connected together to move in

40 unison.

4. A car having an end platform, and a divided door for the side of the platform, said door consisting of two portions mounted to move in transverse directions, one of

45 said portions arranged to form a step when in open position and means for counterbalancing one of said portions.

5. A car having an end platform, said platform having a side doorway, a door 50 composed of two sections, one section controlling the upper portion of the doorway and the other the lower portion of the door-

way, said last mentioned section being hinged below the floor of the platform and rocking, when opened, into position to form 55 a step below the level of the platform floor, and means whereby when the upper door section is moved into and out of closed position, said lower section is coincidentally rocked respectively into position to close the lower 60 portion of the doorway and into position to form a step below the floor of the platform.

6. The combination in a passenger car in which the floor of the platform is below the body of the car, of a sliding door mounted 65 above the sill of the car body and arranged to extend over the platform, with a supplemental door hinged upon a horizontal axis extending longitudinally of the car to swing outwardly into open position to form a step, 70 and operating to close the space between the bottom of the sliding door and the top of the platform when in closed position.

7. The combination in a passenger car, of 75 a platform, a sliding door adapted to close one side of the platform, and a supplemental door for closing the space between the lower end of the sliding door and the platform, said supplemental door being hinged, the hinged axis thereof extending 80 horizontally and longitudinally of the car, whereby said supplemental door may swing outwardly to form a step when in open position with means connecting the supplemental door with the sliding door to cause 85 the two to move in unison.

8. A car having an end platform and a two part door for the side of the platform, the lower part of said door being located beneath the upper part and cooperating 90 therewith, when closed, to close the side of the platform, said lower part being hinged below the floor of the platform, and adapted when open to form a car step below the floor of the platform, the hinge axis of said lower 95 part extending longitudinally of the car.

In testimony whereof I have hereunto set my hand in the presence of the subscribing witnesses, on this 17th day of July A. D., 1908.

JOHN B. BURDETT.
